UNITED STATES PATENT OFFICE.

HERSCHEL RAGSDALE, OF LIBERAL, MISSOURI, ASSIGNOR OF ONE-HALF
TO WILLIAM V. BRADEN, OF LIBERAL, MISSOURI.

WIRE-FENCE-STAPLING MACHINE.

No. 799,496.

Specification of Letters Patent.

Patented Sept. 12, 1905.

Application filed June 30, 1904. Serial No. 214,838.

To all whom it may concern:

Be it known that I, HERSCHEL RAGSDALE, a citizen of the United States, residing at Liberal, in the county of Barton and State of Missouri, have invented a new and useful Wire-Fence-Stapling Machine, of which the following is a specification.

This invention has relation to wire-fence-stapling machines, and has for its object to produce a machine of this character which provides a magazine to carry a large number of staples, is equipped with means to automatically feed the staples toward their point of delivery, has means for locking the automatic feeding mechanism from operation, and which is provided with a spring-actuated delivery slide-plate for picking up the staples one at a time and disposing them in position to be driven into a fence-post or other support.

With these and other objects in view the invention consists in certain novel and peculiar features of construction and organization, as hereinafter described and claimed, and in order that it may be fully understood reference is to be had to the accompanying drawings, in which—

Figure 1 represents a side elevation of a wire-fence-stapling machine embodying my invention. Fig. 2 is a rear view of the same. Fig. 3 is a central longitudinal section taken on the line III III of Fig. 2.

In carrying out the invention a strip of metal notched centrally at one end is bent to U form to produce the elongated magazine 1, having a recess 1^a formed in the upper end of its front wall by bending the plate in line with said notch.

2 designates a U-shaped plate fitting in the lower end of the magazine and forming a bottom therefor, the walls of the plate 2 being secured to the magazine by rivets 3.

4 designates a nose-piece, substantially in the form of an inverted U and riveted, as shown, or otherwise secured upon the upper ends of the side walls of the magazine, said nose-piece in side view being narrower than the magazine, for a purpose which hereinafter appears. The slot or space 5 between the arms 6 and 7 of the nose-piece registers with

the passage of the magazine, but is considerably narrower than the latter for the major portion of its length, flaring downwardly at 8 and 9 until its lower end is of the same width as and flush with the upper end of said

passage, as shown clearly in Fig. 2, the arms 55 6 and 7 at such lower end being preferably notched, as at 10 and 11, to snugly receive the upper ends of the magazine-walls. Arm 7 of the nose-piece is of materially greater thickness by preference than arm 6, so that 60 its inner side shall be approximately in line with the center of the magazine-passage, and in said inner side of said arm is formed a longitudinal groove 12. Riveted, as at 13, in the upper end of said groove is a flat spring 65 14, which normally curves downwardly and meets arms 6 just above the flaring lower end of passage 5 and from said meeting-point curves rearwardly and downwardly, as at 15, and terminates at a point approximately in 70 line with the inner side of arm 7 and about midway the length of the flaring portion of the space or slot 5.

Opposite spring 14 arm 6 is provided with a longitudinal slot 16, through which projects 75 the hook end 18 of tongue 19 of slide-plate 20, fitting flatly against the outer side of the right-hand wall of the magazine, the lower end of said slide-plate being provided with the outwardly-projecting arm 21, to which is riveted 80 the downwardly-projecting thumb-piece or handle 22. The slide-plate is provided with a longitudinal slot 23, mounted upon the guide-pin 24, projecting from the magazine, and bearing against said slide-plate and mounted 85 on said pin is a washer 25, an expansive spring 26, also upon said pin, pressing the washer against the slide-plate, so as to hold the latter with a yielding pressure flatly against the magazine. 90

27 designates a rod extending loosely through arm 21 and thumb-piece 22 of the slide-plate and engaging at its upper end the pin 24, forward of the head of the latter and the spring 26, so that the outer end of the 95 spring by preference bears against said rod, the lower end of said rod being secured rigidly to an angle-plate 29, secured to the magazine, a coil-spring 30, mounted on said rod and bearing at its opposite ends against plate 100 29 and the lower side of arm 21, tending to force the slide-plate yieldingly upward to the position shown.

31 designates a guide-rod secured rigidly at its lower end to the bottom of the magazine 105 and disposed about centrally of the curved portion thereof, said rod tapering upwardly to a point from about the base of the notch

1^a and terminating contiguous to the lower end of spring 14 and in about the same vertical plane, and pivoted to the front side of the magazine is a cap 33, which extends upwardly beyond the upper end of the magazine, converging from the base of notch 1^a rearwardly toward and terminating contiguous to the upper end of the guide-rod 31, as shown clearly in Fig. 3, said cap offering a yielding 10 resistance to the ejection of the staples from the magazine by the spring-actuated feed-plate hereinafter described.

34 designates an angular feed-plate fitting snugly in the magazine and having its horizontal arm fitting slidingly on the guide-rod, the vertical arm of said feed-plate being widened at the rear side of the magazine, so as to provide the vertical shoulders 35 to bear against the rear edges of the magazine side 20 walls to insure direct reciprocatory action.

The feed-plate is provided, by preference, with a shoulder 36 for conveniently depressing it and is also provided with an inwardly-projecting pin 37 for engagement at times 25 with the downwardly-disposed hook portion 39 of a flat spring 38, secured at its lower end to a side wall of the magazine, said downwardly-disposed "spring-hook," as it is herein-after termed, bearing such relation to the 30 pin that when the feed-plate is drawn downward it will repress said spring, so that the latter will spring inward in the upward movement of said pin, and thus lock the feed-plate from upward movement. To effect upward 35 movement of the feed-plate, a coil-spring 40 is mounted on the guide-rod and bears at its opposite ends against the bottom of the magazine and the lower side of the feed-plate.

When it is desired to charge the magazine 40 with staples 41, the feed-plate is lowered until automatically locked against upward movement by the downwardly-disposed spring-hook. The cap 33 is then swung pivotally aside, so as to expose the notch 1^a and permit 45 the operator to slide staples, one at a time, into the magazine until their bridge portions strike the upper end of and are strung upon the guide-rod. They are then released and drop down to a horizontal position until arrested by the feed-plate, the staples piling one upon the other, as shown clearly in Fig. 3, because the space is so narrow that they must 50 assume this relation. The cap is then returned to its original position. When the operator 55 is ready to drive the staples in the fence, he first projects his thumb in the magazine from the rear or open side and represses spring-hook 39 to permit the spring 40 to push the feed-plate upwardly until the topmost staple 60 assumes approximately the position shown in Figs. 2 and 3. He then places his thumb upon thumb-piece 22 and forces the same downward against the resistance of spring 30 until the hook end 18 of the slide-plate snaps 65 between the two topmost staples. The thumb-

piece is then released and spring 30 forces the slide-plate upwardly. In the initial part of this upward movement the topmost staple is tilted upward and toward the rear and engages the overlying portion 15 of spring 14 and 70 forces said spring back in the groove 12 and holds the same in such position until the uppermost leg of said tilted staple registers with or passes into the narrow portion of the slot or space 5, by which time the other leg of 75 said staple has been drawn upward past the end 15 of spring 14, the staple being gradually tilted more and more in the direction indicated by the engagement of its lower arm with the rear side of the downwardly-tapering portion of slot 5, as will be readily understood. As said lower leg of the staple passes above the lower end of spring 14 the latter presses said leg to a position in vertical alignment with the topmost leg, and it continues 80 in such position until the slide-plate has attained its limit of upward movement, when owing to the fact that the nose is narrower from front to rear than the magazine, the bridge or closed end of the staple projects 85 forwardly from said end, so that it can be given a slight tap with a hammer after its pointed ends have been fitted over a wire (not shown) to be secured to a fence-post to embed it in the latter. The operator then places 90 his thumb upon the thumb-piece 22 and draws the slide-plate downwardly until its hooked end 18 is disengaged from the staple. The machine is then pulled forwardly from engagement with the staple and the latter is 95 driven home. All subsequent operations are repetitions of those described until the supply of staples in the magazine has been exhausted, when the machine is again recharged 100 and is then ready for action.

The slide-plate, as described, is caused by the spring 26 to dispose its hook end 18 between the topmost pair of staples each time it attains its lowest limit of movement; but it is to be understood the same action of the 110 slide-plate can be obtained by constructing its tongue 19 of resilient material, so that said tongue may spring into the space below the topmost staple without necessitating the use of the spring 26, in other words, without necessitating the body portion of the slide to 115 operate pivotally on its guide-pin 24.

From the above description it will be apparent that I have produced a wire-fence-stapling machine which possesses the features 120 of advantage enumerated as desirable in the statement of the object of the invention and which obviously may be modified in its form, proportion, detail construction and arrangement of the parts without departing from the 125 spirit of construction involved.

Having thus described the invention, what I claim as new, and desire to secure by Letters Patent, is—

1. A stapling-machine, comprising a maga- 130

zine, a nose secured to one end thereof and provided with a slot communicating with the magazine-passage and having its connecting end flaring toward said passage, a guide-rod 5 extending longitudinally of the magazine within its passage, a depending spring secured to the nose at one side of its slot and converging downward toward the opposite side and then diverging away from the last-named side 10 and terminating just above and approximately in line with the top of said guide-rod, means to support staples threaded on said guide-rod, 70 and a reciprocatory plate having a hook terminal projecting yieldingly into the path of movement of the staples to remove the topmost one and dispose it in a position substantially at right angles to its original position in the slot of the nose. 75

2. A stapling-machine, comprising a magazine, a nose secured to one end thereof and provided with a slot communicating with the magazine-passage and having its connecting end flaring toward said passage, a guide-rod 20 extending longitudinally of the magazine within its passage, a depending spring secured to the nose at one side of its slot and converging downward toward the opposite side and then diverging away from the last-named side 25 and terminating just above and approximately in line with the top of said guide-rod, means to support staples threaded on said guide-rod, 30 means for yieldingly elevating the staple-supporting means, and means to successively remove said staples and dispose them in the slot of the nose in a position substantially at right angles to that which they occupied in 35 the magazine.

3. A stapling-machine, comprising a magazine, a nose secured to one end thereof and provided with a slot communicating with the magazine-passage and having its connecting 40 end flaring toward said passage, a guide-rod extending longitudinally of the magazine within its passage, a depending spring secured to the nose at one side of its slot and converging downward toward the opposite side and 45 then diverging away from the last-named side and terminating just above and approximately in line with the top of said guide-rod, means to support staples threaded on said guide-rod, 50 means for yieldingly elevating the staple-supporting means, means to lock said staple-supporting means from upward movement, and means, when the staple-supporting means is free to move upward, for successively removing said staples and disposing them in the 55 slot of the nose in a position substantially at right angles to that which they occupied in the magazine.

4. A stapling-machine, comprising a magazine, a nose secured to one end thereof and 60 provided with a slot communicating with the magazine-passage and having its connecting end flaring toward said passage, a guide-rod extending longitudinally of the magazine within its passage, a depending spring secured 65 to the nose at one side of its slot and converging

downward toward the opposite side and then diverging away from the last-named side and terminating just above and approximately in line with the top of said guide-rod, means to support staples threaded on said guide-rod, 70 and a reciprocatory plate having a hook terminal projecting yieldingly into the path of movement of the staples to remove the topmost one and dispose it in a position substantially at right angles to its original position in the slot of the nose.

5. A stapling-machine, comprising a magazine, a nose secured to one end thereof and provided with a slot communicating with the magazine-passage and having its connecting 80 end flaring toward said passage, a guide-rod extending longitudinally of the magazine within its passage, a depending spring secured to the nose at one side of its slot and converging downward toward the opposite side and then 85 diverging away from the last-named side and terminating just above and approximately in line with the top of said guide-rod, means to support staples threaded on said guide-rod, a slide-plate having a hook-terminal projecting 90 yieldingly into the path of movement of the staples, and means for yieldingly elevating said slide-plate, so as to raise the topmost staple and dispose it in a position substantially at right angles to its original position in the 95 slot of the nose.

6. A stapling-machine, comprising a magazine, a nose portion at one end of the magazine, provided with a slot communicating with the magazine-passage and flared toward said 100 passage at the point of connection therewith, yielding means opposing the entrance of the staples into the slot of the nose portion, and means arranged to reciprocate on and lengthwise of the machine, for engaging 105 one leg of the staple nearest said slot and pushing said staple therein against the resistance of said yielding means.

7. A stapling-machine, comprising a magazine, a nose portion at one end of the magazine, provided with a slot registering with the magazine-passage and flared toward said 110 passage at the point of connection therewith, a reciprocatory slide having a resilient end adapted to successively remove staples from 115 said passage and dispose them in the slot of the nose portion, and yielding means to permit a staple to enter the slot when pushed by said slide.

8. A stapling-machine, comprising a magazine, a nose portion at one end of the magazine, provided with a slot registering with the magazine-passage and flared toward said 120 passage at the point of connection therewith, a guide-rod extending longitudinally of and 125 within the magazine-passage, a cap converging upward with the rod to prevent the accidental ejection of these staples from the magazine-passage, means to overcome the resistance of the cap and successively remove 130

staples from said passage and dispose them in the slot of the nose portion, and yielding means to permit a staple to enter the slot when pushed by the means which overcomes the resistance of the cap.

9. A stapling-machine, comprising a magazine, a nose portion at one end of the magazine, provided with a slot registering with the magazine-passage and flared toward said passage at the point of connection therewith, a spring-actuated feed-plate underlying the staples in the magazine-passage, means to hold the same retracted, means to successively re-

move staples from the magazine when the feed-plate is free to advance, and yielding means to permit a staple to enter the slot when pushed from the magazine-passage by the said staple-removing means.

In testimony whereof I have hereunto signed my name to this the above specification. Done in the presence of two witnesses subscribing their respective names hereto.

HERSCHEL RAGSDALE.
